[57] CLAIM

The ornamental design for a vehicle tire tread, as shown
and described.

DESCRIPTION

FIG. 1 is a fragmentary perspective view of a vehicle
tire tread showing my new design, it being understood
that the tread pattern is repeated throughout the cir-
cumference of the tire carcass, as shown schematically
by broken lines, the opposite side being substantially the
same as that shown;

FIG. 2 is an enlarged fragmentary top plan view
thereof; and

FIG. 3 is an enlarged fragmentary side elevational view
thereof.
